DESIGN FOR A PENCIL FERRULE

Elroy S. Mallard, Georgetown, Ky.

Application February 13, 1946, Serial No. 126,536

Term of patent 14 years

(CL. D74—1)

To all whom it may concern:

Be it known that I, Elroy S. Mallard, a citizen of the United States, residing at Georgetown, Kentucky, have invented a new, original, and ornamental Design for a Pencil Ferrule, of which the following is a specification, reference being had to the accompanying drawing, forming part thereof.

Figure 1 is a plan view of the pencil ferrule showing my new design.

Figure 2 is an end view.

Figure 3 is a cross sectional view taken on the line 3—3 of Figure 1.

I claim:

The ornamental design for a pencil ferrule, as shown.

ELROY S. MALLARD.
